[57] CLAIM

The ornamental design for a rotating spout for liquid containers, as shown and described.

DESCRIPTION

FIG. 1 is a perspective view of our new design, showing the spout in the open position;

FIG. 2 is a top plan view showing the spout in a closed position;

FIG. 3 is a rear elevational view with the spout in a closed position;

FIG. 4 is a front elevational view with the spout in an open position; and,

FIG. 5 is a side elevational view with the spout in a closed position.

The broken line showing of a container neck is for illustrative purposes only and forms no part of the claimed design.
